UNITED STATES PATENT OFFICE.

WILLIAM DUNN, OF ELK, WYOMING.

SELF-ADJUSTING TRACK-BRACE.

1,272,236.

Specification of Letters Patent.

Patented July 9, 1918.

Application filed February 28, 1918. Serial No. 219,614.

To all whom it may concern:

Be it known that I, WILLIAM DUNN, a citizen of the United States, residing at Elk, in the county of Lincoln and State of Wyoming, have invented a new and useful Improvement in Self-Adjusting Track-Braces, of which the following is a specification.

This invention relates to a new and useful 10 improvement in self-adjusting track braces.

The principal object of my invention is to provide a track brace which is adjustable to different size rails wherever located, for the purpose of maintaining the gage 15 of the rails and preventing the rails from tipping when a train is running over them.

The preferred form of embodiment of my invention is illustrated in the accompanying drawings of which Figure 1 is a 20 plan view of my self-adjusting brace applied to the two rails of a track. Fig. 2 is a front elevational view of my invention, showing the rails in section. Fig. 3 is a vertical section taken on the line b—b of Fig. 1. Fig. 4 is an end view of the device. And Fig. 5 is an outline end view of a 25 standard rail, for the purpose of illustrating my invention.

Throughout the specification and drawings, similar reference characters denote 30 corresponding parts.

In a detailed description of the preferred form of embodiment of my invention, the numerals 1 1 designate a pair of rails laid 35 in parallel alignment to form a track, while the numeral 2 designates an elongated bolt which cooperates with the parts now to be described in holding the rails 1 1 to gage and preventing their spreading when a train 40 passes over them.

Adapted to be slipped over the bolt 2, to a position near its middle portion, is a short sleeve 3. However, before the sleeve is applied to the bolt 2, a washer 4 is 45 dropped on the latter to rest against its head. This washer 4 has an inclined inner side adapted to slide, in the direction of the line a—a, upon the inclined portion of a bracing member 5 now to be described.

50 Referring to Figs. 1, 2 and 3, there are provided for each rail 1, two bracing members 5 5, each of which comprises an inclined portion upon which the washer 4 slides, and in which there is a lateral hole 55 adapted to loosely receive the bolt 2. Each of the braces 5 has a forked end, the upper

prong of which is adapted to engage the web of the rail, while the lower prong is pivotally connected to a corresponding prong of another brace. 60

After a washer 4 is dropped on the head end of the bolt 2, and a pair of braces 5 5 is applied to a rail 1 so that their upper prongs engage its web, the bolt 2 is slid under said rail and through the lateral holes 65 in the braces, after which a second washer 4 is applied to said bolt. The sleeve 3 and a third washer 4 are then applied to the bolt 2, after which it is thrust through the holes in a second pair of braces 5 5 applied 70 to the second rail 1, whereupon a fourth washer 4 is applied to the bolt. A nut 6 is then screwed on the threaded end of the latter.

The lower forked portions of each pair 75 of braces 5 5 are pivotally connected as at 7, so that when the nut 6 is tightened, the washers 4 which are caused thereby to ride up the inclined portions of the braces 5 5, not only carry the bolt 2 upwardly into engagement with the feet of the rails, but also cause the upper prongs of the braces to firmly engage the webs of the rails, the sleeve 3 communicating the lateral thrust from the second pair of braces to the first. 80 Accordingly, the more the nut 6 is tightened, the more firmly will the rails be gripped by the braces to hold their gage and prevent their spreading under the most adverse conditions. 85

In order to guide the washers 4 during their up and down movement upon the braces 5 5, the inclined portions of the latter are provided with slots 8 to receive projections or teats 9 on the washers, said slots and projections also serving to prevent a turning or side movement of said washers. (See Fig. 1.) 90

My improved brace is not only adapted to firmly hold the gage of rails to which it 100 is applied, but it is adjustable in that it may be applied to different size rails at any place, without changing the length of the sleeve 3 or altering other parts. In other constructions with which I am 105 familiar, the sleeve 3 must be of different lengths to accommodate the brace to different size rails.

Upon observation I find that as the weight of the rail decreases, the width 10 of the 110 top, and the height 11 of the bottom, of the rail (see Fig. 5) will also decrease. Ac-

cordingly, the smaller rail permits the braces 5 to approach nearer each other, and, in conjunction with their pivotal action, increases the inclination of their inclined faces, or the 10 line $a-a$, to permit the washers 4 to ride farther up toward the rail when the nut 6 is tightened, thereby moving the rails toward each other a distance sufficient to make up for the decrease in the width 10 of their 15 tops. In the case of the larger rail, the inclination of the line $a-a$ will be decreased, whereupon the washers will not be permitted to ride as far up toward the rail as in the first instance and the rails will be maintained a sufficient distance apart to make up 20 for the increase in the width 10 of their tops. Therefore the rails will be kept at the same gage by my improved braces irrespective of their size.

20 I do not wish to be limited to the details of construction and arrangement herein shown and described, and any changes or modifications may be made therein within the scope of the subjoined claims.

25 Having described my invention, I claim:

1. In a device of the type specified, the combination with a pair of rails in track alinement, of a pair of forked clamping braces for each rail, the upper prongs of 30 each pair of braces adapted to engage the web of the rail from opposite sides, while the lower prongs of said braces are pivotally connected together, an elongated member laterally movable through holes in said 35 clamping braces below their forked ends, a head on one end of said elongated member, a nut adapted to be applied to its other end, and slidable means on said member adapted to be moved upon the braces when the nut 40 is tightened, to draw the elongated member tightly against the feet of the rails and to press the upper prongs of the braces firmly against the web portions of said rails.

2. In a device of the type specified, the 45 combination with a pair of rails in track alinement, of a pair of forked clamping braces for each rail, the upper prongs of each pair of braces adapted to engage the web of the rail from opposite sides, while the lower 50 prongs of said braces are pivotally connected together, an elongated bolt laterally movable through holes in said clamping braces be-

low their forked ends, a nut adapted to be applied to the threaded end of said bolt, a 55 slidable member on said bolt adapted to be moved upon the upper portion of a brace when the nut is tightened, and a sleeve on said bolt, interposed between the two innermost slidable members.

3. In a device of the type specified, the 60 combination with a pair of rails in track alinement, of a pair of inclined clamping braces for each rail, the upper end of each brace being forked, the lower prong of each pair of braces being pivotally connected together, while their upper prongs are adapted to engage the web portion of the rail from opposite sides, an elongated bolt laterally movable through holes provided in the inclined portion of the said braces below their 65 forked ends, a nut adapted to be applied to the threaded end of said bolt, a sleeve on the middle portion of said bolt, and a slidable washer on said bolt, on each side of said sleeve, and at each end of the bolt, each 70 washer having an inclined inner end adapted to be moved upon the upper prong of an adjacent brace when said nut is tightened.

4. In a device of the type specified, the 75 combination with a pair of rails in track alinement, of a pair of inclined clamping braces for each rail, the upper ends of each brace being forked, the lower prongs of the forked portions of each pair of braces being pivotally connected together, while their upper prongs are adapted to engage the web portion of the rail from opposite sides, an 80 elongated bolt laterally movable through holes provided in the inclined portions of said braces below their forked ends, a nut adapted to be applied to the threaded end of said bolt, a slidable washer on said bolt adapted to be moved upon the upper portion of an adjacent brace when the nut is tightened, a slot in the upper portion of each 85 brace, and a projection on a washer adapted to enter its respective slot to guide it during its up and down movement on the brace.

90 In testimony whereof I have hereunto set my hand this 26th day of February, 1918. 95

100 WILLIAM DUNN.
